UNITED STATES PATENT OFFICE.

EDWARD ANDERSON, OF MARCH, SOUTH DAKOTA.

DESIGN FOR A FENCING-TOOL.

SPECIFICATION forming part of Design No. 31,282, dated July 25, 1899.

Application filed April 8, 1899. Serial No. 712,350. Term of patent 7 years.

To all whom it may concern:

Be it known that I, EDWARD ANDERSON, a citizen of the United States, residing at March, Charles Mix county, State of South Dakota,
5 have invented and produced a new and original Design for a Fencing-Tool, of which the following is a specification, reference being had to the accompanying drawing, which is a perspective view of my design.

10 The tool shown in the drawing is a fencing-tool, serving as a wire-tightener, staple-puller, and hammer.

15 The features of my design consist of the shoulder 2, dividing the ends A and B of the tool, the end 3 of the portion A being curved

and pointed in shape, as shown. The opposite portion B of the tool has a curved and pointed end 4, and between the end 4 and the center of the tool is a laterally-projecting head 5.

20

I claim—

The design for a fencing-tool, as herein shown and described.

In testimony whereof I affix my signature in the presence of two witnesses.

EDWARD ANDERSON.
